UNITED STATES PATENT OFFICE.

MYLES H. ROYER, OF PORTLAND, OREGON, ASSIGNOR OF FORTY-NINE ONE-HUNDREDTHS TO LAWRENTZ B. SANDEBLAST, OF PORTLAND, OREGON.

ADDING MACHINE.

Application filed December 24, 1925. Serial No. 77,545.

This invention is directed to an improvement in adding machines, constructed primarily with a view to permitting all necessary and desirable operations incident to such machines, while at the same time materially reducing the number of parts and simplifying the cooperation of such parts to reduce the cost of manufacture.

The present invention has for its object 10 the provision of an adding machine, in which, through the use of the usual key levers, the number to be added may be set up on the number wheels and added to the totalizing wheels, with simple provisions for carrying over from one wheel to the next higher digit wheels. A simplified construction is provided whereby at will the numbers set up on the number wheels or on the totalizing wheel may be readily printed; 15 the construction providing a resetting mechanism to restore the wheels to normal or starting position.

The invention is illustrated in the accompanying drawings, in which:

25 Fig. 1 is a view in longitudinal section of the improved adding machine.

Fig. 2 is a plan of the same, the casing being partly broken away.

30 Fig. 3 is a view in elevation, partly in section, showing the means for operating the number wheels in the actuation of the key levers, and the means whereby all the number wheels are advanced for printing.

Fig. 4 is a plan view of the same.

35 Fig. 5 is a view in elevation, partly in section, showing the means for setting the totalizing wheels and also the means for advancing said totalizing wheels for printing.

40 Fig. 6 is a broken elevation showing the means for operating the mechanism for advancing the number wheels to printing position.

Fig. 7 is a plan view of the construction shown in Fig. 5.

45 Fig. 8 is a view in elevation illustrating the resetting means.

Fig. 9 is a section on line 9—9 of Fig. 8.

50 Fig. 10 is a broken view in elevation showing the key restoring means, and also indicating the means for permitting independent movement of the totalizing wheel operating segment.

Fig. 11 is a plan of the same.

Fig. 12 is a broken perspective view of a

portion of a key lever showing the formation 55 of the hub thereof to permit the independent movement of the totalizing wheel operating segments.

Fig. 13 is an edge view of the same.

Fig. 14 is a view of the mounting of the 60 totalizer wheel shaft.

Fig. 15 is a view in elevation of the carry-over mechanism.

Fig. 16 is a side elevation of the same.

The improved adding machine comprises 65 a readily portable structure, including a base 1, and a casing cover 2, removably secured to the base and appropriately formed to house the mechanism, the upper wall of the casing cover having a convex section 70 3, formed with a series of longitudinally ranging parallel slots 4 for the manual adjustment of the key levers. The casing wall adjacent the slots is marked with appropriate numbers to indicate the proper position of the key levers in setting up particular numbers.

A shaft 5 is mounted in the side walls of the casing and rotatively supports a series of independently mounted key levers 6, 80 adapted to project through the respective slots 4 and each provided beyond the casing with a handle portion 7. If desired, and as preferred, one wall of each of the slots 4 may be formed with indentations 8, aligning with the particular numerals adjacent such slot, and the corresponding key lever provided with a spring pressed element 9 adapted to engage in said indentations to more or less accurately position the lever and at the same time prevent casual displacement thereof.

Integral with the hub of each lever 6 is a number wheel operating segment 10 having operating teeth 11, arranged concentric to the axis of the key lever and adapted to cooperate with the number wheels for setting up the numbers in accordance with the movement of the key levers. These segments 10 will be hereinafter termed the 100 number segments. An additional or totalizing segment 12 is also mounted on and movable with the hub of each key lever, these totalizing segments having peripheral concentrically arranged teeth 13 for cooperation 105 with the totalizing wheels. The totalizing segments are mounted for a limited relative movement with respect to the hubs of

the particular key levers, in order to permit the carrying over from one totalizing wheel to the next while a segment is engaged therewith. The particular construction for this purpose will be later explained.

A number wheel shaft 14 is mounted at its ends in the side walls of the casing cover in a manner to permit a sliding movement of the shaft longitudinally of the casing, and on this shaft are mounted number discs 15, having appropriate peripheral numbers from zero to nine also blanks. Adjacent each number disc or wheel, and secured to or forming a fixed part thereof, is a pinion 16 having peripheral teeth 17 to be engaged by the teeth 11 of the particular key lever number segment 10, thus permitting the particular number wheel to be set up with the desired number through the operation of the corresponding key lever to that number indicated on the casing cover. A totalizing wheel shaft 18 is mounted below the number wheel shaft 14. The ends of this shaft are slidably supported in slotted bearings 19 in the walls of the casing, and on the shaft are a series of totalizing discs 20 having appropriate peripheral numbers from zero to nine and each having a relatively fixed pinion 21 arranged in the path of movement of the particular totalizing segment 12 on the corresponding key lever. It is to be noted from Fig. 1 in the drawings that while the number segments 10 are normally in engagement with the pinions of the number wheels, the totalizing segments 12 are normally out of engagement with the pinions of the totalizing wheels. Thus in normal position, the totalizing wheels are free of engagement with the totalizing segments, so that in the operation of any one of such segments, through movement of the key lever, a carrying over between the totalizing wheels is readily permitted without interference from the totalizing segments.

An important detail of the present invention resides in the means whereby the number wheels and totalizing wheels may from time to time as desired be moved to printing position for indicating the successive numbers set up on the number wheels and the total of any desired series of such numbers. For the purpose of receiving the impressions from the respective sets of wheels, I provide the usual paper tape 22 from a reel supply 23 supported beyond the casing, the tape being led over guide rollers 24 and over an intermediate platen 25 on the inner side of the rear wall of the casing cover. The usual inked ribbons 26 and 27 from spools 28 are fed by any appropriate mechanism over the surface of the paper tape in the printing line of the number wheels and totalizing wheels. For the printing movement of the number wheels, it will be seen that the shaft 14 is mounted

adjacent its respective ends in bearing 29 carried by longitudinally ranging bars 30, supported in guides 31 fixed to the casing. At their ends remote from the number wheels, that is, at the front end of the casing, the bars 30 bear against discs 32 eccentrically mounted on a shaft 33 supported at its ends in the casing, and provided at an appropriate point with a pinion 34 to be engaged by a segment 35 mounted upon a shaft 36 supported in the casing and provided beyond the same with a handle 37 which may be termed the number printing handle.

As will later appear, the actuation of the number printing handle operates automatically to restore all of the set or operated key levers to normal or inoperative positions, and under these conditions it is of course necessary that during this resetting of the key levers, the totalizing wheels be out of engagement with the totalizing segments of the operated key levers. Otherwise, this resetting of the key levers would reset the totalizing wheels or if such could not be moved rearward, would tend to a breakage of the parts. The following provision is therefore made to move the totalizing wheels beyond the possible influence of the totalizing segment, without permitting a printing movement of such totalizing wheels, under the operation of the number printing handle 37.

To secure this desired movement of the totalizing wheels as a unit, a shaft 38 is mounted in the casing below the shaft 33, on which shaft 38 is provided a disc 39 to which is connected a link 40, in turn secured to totalizing wheel operating bars 41, to be later described. A toothed segment 42 is secured upon the shaft 38, and is engaged by a pinion 43 on the shaft 36. The proportions of the segment 35 and pinion 34 are such that in the predetermined movement of the handle 37, the bars 30, and therefore the number wheels, will be moved to printing position, that is, to impress the numbers set up on said wheels through the inked ribbons 26 onto the paper tape 22 and back again to normal position. The relative proportions of the segment 42 and pinion 43 however, are such that in the movement of this handle, the bars 41 will be moved a materially less distance than the bars 30, so that as the number wheels are moved to printing position and back again, the totalizing wheels will be moved toward but not to printing position, thus arranging the totalizing wheels beyond the influence of the totalizing segments. Springs 44 connected to the casing and to the bars 30, tend to return the number wheels to normal position in the return movement of the handle 37, the totalizing wheels being in this movement of the handle drawn to normal position.

It is of course necessary to provide for a printing operation of the totalizing wheels in order that the final product of any series of operations of the machine may be had, and this of course necessitates providing for two independent movements of the totalizing wheels as a unit, one incident to their partial movement during printing movement of the number wheels, and another incident to their full printing movement.

To provide for the printing operation of the totalizing wheel unit, a shaft 45 is mounted transverse the casing below the bar 41, and an operating handle 46, hereinafter termed the totalizer printing handle, is connected to one end of the shaft beyond the casing. Secured to the shaft within the casing is an arm 47, connected to a bar 48, slidably mounted in the guides 31, and bearing at its forward end against the shaft 18. Of course the arm 47 and bar 48 is duplicated at the opposite side of the casing, and it is obvious that upon operation of the totalizer printing handle 46, the totalizer wheel unit may be advanced to print the numbers set up thereon on the paper. Of course it will be remembered that this totalizer wheel unit is actuated partly towards printing position by bars 41, and to permit the unit to move to printing position without operating the bars 41, the latter, as indicated in Fig. 14, are terminally formed with an open box-like end 49, through which the shaft 18 passes, and in which the shaft is held at one end of the box 49 by a spring 50 bearing against a follower 51 formed to partly embrace the shaft. By this construction, the totalizer wheel unit may be moved a portion of the distance toward printing position, as when operating the number wheel printing handle, or be moved the full distance to printing position as when operating the totalizer printing handle 46.

In connection with the operation of the number wheels to printing position, provision is made for automatically restoring all of the operated key levers to normal or starting positions, the resetting movement being accomplished as the number wheel printing handle 37 is being retracted from printing position. The resetting mechanism includes a bar 52 supported in advance of the key levers by arms 53 freely rotatable on shaft 5. Each of the arms is provided with a forwardly extending rod 54, terminating in a rectangular yoke 55, having a projection 56 extending downwardly from its upper wall. An arm 57 extends from shaft 36 and has a lateral pin 58 to normally play in the yoke 55 and to engage the projection 56 when in appropriate position. The cam tracks 59 having upper inclined surfaces are arranged in position to be engaged by the forward ends of the

yokes 55 to bodily elevate the yokes as such yokes reach a predetermined position in operation.

In the key resetting mechanism, it will be apparent that in the operation of the first key lever, the bar 52 will be moved forwardly, thus freeing all the key levers and causing the bar to follow forward that key lever which may be operated the limit in that direction. As the bar 52 is moved, the yokes 55 are correspondingly moved forward, as indicated in dotted lines in Fig. 10. On movement of the number wheel printing handle to the left to move the number wheels to printing position, the pin 58 on the arm 57, will ride lengthwise the yoke 55 and finally in rear of the projection 56. As the printing handle is returned to normal position, the pin 58, through engagement with the projection 56, will force the bar 52 forwardly and thus restore to normal position all operated key levers. As the movement continues, the yoke will engage the cam track 59 and be gradually raised until when the parts have reached their normal positions, the projection 56 will be raised out of the path of the pin 58, and no further movement of the bar 52 will be caused, though it is understood at this time the number wheels have not been fully returned to normal position.

It will of course be apparent that as the key levers are returned to normal position, the number segments and totalizing segments will be correspondingly returned to normal position, and if during this operation the totalizing segments have been in mesh with the pinions of the totalizing wheels, the movements of the wheels would have been reversed exactly to the same extent that they had previously been set up. It is for this reason that in the printing movement of the number wheels the totalizing wheel unit is moved forward wholly free of influence of the totalizing segment, so that in the resetting of the key levers, the totalizing wheels are not effected.

It may frequently happen that while a totalizing segment is in cooperation with the pinion of a particular totalizing wheel through the operation of a key lever, that such totalizing wheel will be advanced through the carry over mechanism from the operation of the preceding wheel. Under these circumstances, each totalizing segment must be capable of independently yielding a definite distance on each side of a normal position relative to its key lever in order to compensate for this carry over operation in either direction of the engaged wheel, as for example, in addition or subtraction. To secure this permissible adjustment of the totalizing segment relative to the key levers, the hub of such key lever is cut away at 60 and formed with a central recess 61 and

end recesses 62 and 63. The segment is formed with a spring plate 64 having a pin 65 adapted to seat in either of said recesses. Normally the pin will occupy the central recess and the construction thus provides for an independent yielding of the totalizing segment in either direction from normal under operating stress on the particular totalizing wheel without disturbing 19 the key lever.

In the possibility that one or the other of the totalizing segments will be moved from normal relation to its key lever during the use of the machine, it is of course necessary 15 to restore such totalizing segments to normal position. For this purpose, the pressure bar 66 is pivotally supported at 67 on a transverse rod, with the long length of the bar in position to be engaged by the square 22 end 68 of the totalizing segment. The short length of the pressure bar is in position to be engaged by the key lever. There is of course one such pressure bar for each totalizing segment, and as the key lever is operated 28 and the totalizing segment moved upwardly, the pressure bar is correspondingly tilted or turned on the pivot bar, without in any way effecting the movement of the segment. When the key levers are reset, the key 34 levers engage the short ends of the pressure bars with a tendency to turn them about the pivot rod 67, thus forcing the long ends against the square end 66 of the totalizing 41 segment and moving all such segments into 25 contact with a limit rod or pin 69 projecting from the casing. Therefore, as the key levers are reset, all totalizing segments will be moved to normal position, that is, with the pin 65 in the central recess 61 of the hub 50 of the key lever.

The carry over mechanism is illustrated more particularly in Figs. 15 and 16 and is of conventional form, the discs bearing the numbers are provided with plain discs 70 formed at an appropriate point with a toothed recess 71. A shaft 72 is arranged beyond the disc and carries transfer wheels 73 formed with narrow and wide teeth 74, 75, so that, as is usual in this type of mechanism, when a particular disc reaches the zero position and numbers are added in, the adjacent disc will be advanced one tooth. The form here shown is that conventionally employed and a further detailed description thereof is not deemed necessary.

It will be further noted that as the number wheels are moved to printing position, the number segments and totalizing segments are freed of retarding influence and 60 might be easily disarranged by accident, so that on the return of the numbering wheels from printing position and the consequent resetting movement of the levers, the numbering wheels would not be restored to zero 65 position.

The locking mechanism for the segments is illustrated more particularly in Fig. 3, wherein it will be noted that the bars 30 for moving the number wheels to printing position are provided at an appropriate point 70 with a depending projection forming a cam lug 76. Supported on the casing adjacent each bar 30 is an angle lever 77 pivotally supported at 78 and having its forwardly projecting arm provided with a laterally extending pin 79, adapted to be engaged by the cam lug 76 in that movement of the bars tending to actuate the number wheels to printing position. The opposite terminal of the angle lever is connected to a pin and slot 80 connection 80, with the side bars of a sliding frame 81, operative in guides 82 on the casing, and including a cross bar 83 on which are fixed gear segments 84 having their teeth 85 in position to engage the teeth 85 11 of the number segments 10, which segments may be extended, if desired, to secure locking cooperation with the locking sectors 84 in all positions of the key levers.

From the above construction it will be understood that as the bars 30 start to move for printing operation of the number wheels, the angle lever 77 is rocked against the influence of a restoring spring 86, with the effect to draw down the frame 81 and cause 95 the teeth 85 of the sectors 84 to engage the number sectors 10 and obviously lock the same against movement.

Provision is made for resetting the totalizing wheels to zero or normal position, the 100 construction being illustrated particularly in Figs. 8 and 9. As shown, the clearing mechanism comprises a bar 87 overlying the totalizing wheels, with its ends connected to a handle 88 supported loosely upon the shaft 105 18 beyond the casing, the bar 87 being capable of radial play but normally held at its outward limit by a spring 89. The bar 87 overlies the totalizing wheels, and in alignment with each of such is formed with 110 means to engage each of said wheels, such for example, as a spring pressed pin 90 co-operating with a recess 91 in the totalizing wheel. The bar 87 extends at its ends through a guide 92 in the form of a circular 115 member concentric with the totalizing wheels and mounted for longitudinal movement relative to the casing by a pin and slot connection 92' to permit this guide to move with the totalizing wheel unit, in the 120 operations thereof described. The annular guide 91' is formed with an offset 93 which is of a size to receive the bar 87, under the influence of the spring 89, with the offset 125 so formed that when the bar is in the offset, the pins 90 are out of engagement with the recesses 91 in the totalizing wheels. As the handle 88 is turned however, the bar 87 is forced toward the totalizing wheels, with the effect to cause the pins 90 to engage in 130

the particular recesses 91 of the totalizing wheels. In a full travel of the bar 87, all the totalizing wheels will be picked up and turned to a position so that all of their recesses 91 will be in alignment transversely of the casing immediately beneath the offset 93 of the guide 91'. At this point, the bar 87 will be pressed into the offset, freeing the totalizing wheel. It is of course understood that when the recesses 91 of the totalizing wheels are in this position, the zero figures on each of said wheels will be in printing line, that is, the totalizing wheels will be in normal positions.

15 It will be noted that the construction as a whole provides an adding machine in which the usual tabulating or number wheels may be set up through the operation of the key levers, such levers serving at the same time to set up the totalizing wheels, the number wheels or totalizing wheels being operated for printing at will, with all operated key levers automatically restored to normal position during the movement of the 20 number wheels from printing to operative positions; the automatic locking of the key levers against casual displacement during the printing operation of the number wheels; and the clearing up of the totalizing 25 wheels, with the mechanisms leading to the carrying out of these operations of a simple compact nature involving the use and requirements of but few parts, whereby the machine as a whole, while capable of performing all the functions of the usual adding machine, is materially simplified to insure more certainty of operation and material less cost in manufacture.

It is to be noted that there is provided 40 in shaft 33, a clutch 94 through which the handle 37 is permitted to be returned to normal position without operating the parts, the clutch slipping in this movement and through which the handle 46 may be operated without similarly actuating the handle 37.

Claims:

1. A device of the class described having 45 number wheels, key levers selectively operable to set up the number wheels, and means for moving the number wheels to a printing position, means operable by the set-up means of the number wheels to operate totalizing wheels, and means operable in the movement 50 of the number wheels to printing position to simultaneously move the totalizing wheels beyond the influence of the key lever.

2. A device of the class described, having 55 number wheels, totalizing wheels, key levers selectively operable to set up the number wheels and totalizing wheels, and means for moving the number wheels to a printing position, means automatically set in the 60 operation of any key lever for restoring the

operated key levers to normal position in 65 and by the means for moving the number wheels to printing position, and means for automatically disconnecting the key lever restoring means at a predetermined point in the operation of the number wheel printing 70 wheels.

3. A device of the class described having 75 number wheels, totalizing wheels, key levers for setting up the number wheels and totalizing wheels, and means for moving the number wheels to printing position, a handle for operating said means, and mechanism whereby said handle will move the totalizing wheels beyond the influence of the key levers when operating to move the number wheels 80 to printing position and then into cooperation with the key levers in a single movement of the handle in one direction.

4. A device of the class described having 85 number wheels, totalizing wheels, key levers operable to set up the number wheels and totalizing wheels, and a setting bar for moving the number wheels to printing position, a handle for operating said bar, a restoring bar automatically operated in the movement 90 of any key lever, and means actuated in the movement of said setting bar to operate the restoring bar to restore the keys to normal position.

5. A device of the class described having 95 number wheels, totalizing wheels, key levers for setting up the number wheels and totalizing wheels, and a segment carried by each key lever to operate the totalizing wheels, means for mounting said last mentioned segment 100 on its key lever to permit a limited independent movement of such segment relative to the key lever under a turning stress of the totalizing wheel.

6. A device of the class described having 105 number wheels, totalizing wheels, key levers for setting up the number wheels and totalizing wheels, a segment carried by each key lever to operate the number wheels, a second segment carried by each key lever to operate 110 the totalizing wheels, said second segment being capable of independent movement relative to the key lever under a particular stress of the totalizing wheels, means for restoring the key levers to normal positions, and means operated by the key levers to position all operated second segments to a 115 predetermined normal position.

7. A device of the class described having 120 number wheels, totalizing wheels, key levers for setting up said number wheels and totalizing wheels, a segment on each key lever for operating a number wheel, a frame supporting the number wheels, and means for operating the frame, a segment carried 125 by each key lever for operating a totalizing wheel, a frame supporting all totalizing wheels, and means for operating the totaliz-

ing wheel supporting frame to move the totalizing wheels beyond the influence of their segments simultaneously with the operation of the frame for supporting the number wheels.

8. A device of the class described having number wheels, totalizing wheels, a frame for slidably supporting said number wheels including side bars, a shaft having a cam to engage the ends of the side bars, and a manually operable member for actuating said cam, a frame for supporting the totalizing wheels, and an eccentric connected with said frame, said eccentric being operated by said manually operable member simultaneously with the operation of said cam.

9. A device of the class described having number wheels, totalizing wheels, a frame for slidably supporting said number wheels including side bars, a shaft having a cam to engage the ends of the side bars, and a manually operable member for actuating said cam, a frame for supporting the totalizing wheels, and an eccentric connected with said frame, said eccentric being operated by said manually operable member simultaneously with the operation of said cam, said eccentric operating the totalizing wheel frame to a less extent than the movement of the number wheel supporting frame under said cam.

10. A device of the class described, having number wheels, totalizing wheels, carry-over mechanism for the totalizing wheels, key levers, and a segment carried by each key lever to operate the number wheels, a segment carried by each key lever to operate the totalizing wheels, and means to permit the totalizing wheel operating segment to yield under carry-over movement of a total-

izing wheel without interrupting the relation of the segment and totalizing wheel.

11. A device of the class described, having number wheels, totalizing wheels, carry-over mechanism for the totalizing wheels, key levers, and a segment carried by each key lever to operate the number wheels, a segment carried by each key lever to operate the totalizing wheels, each totalizing wheel operating segment being mounted for limited movement with relation to its key lever in either direction beyond the normal position of such segment to an extent necessary to permit a carry-over movement of a particular totalizing wheel in either addition or subtraction without disturbing the relation between such segment and its totalizing wheel.

12. A device of the class described, having number wheels, totalizing wheels, carry-over mechanism for the totalizing wheels, key levers, and a segment carried by each key lever to operate the number wheels, a segment carried by each key lever to operate the totalizing wheels, each totalizing wheel operating segment being mounted for limited movement with relation to its key lever in either direction beyond the normal position of such segment to an extent necessary to permit a carry-over movement of a particular totalizing wheel in either addition or subtraction without disturbing the relation between such segment and its totalizing wheel, means for restoring the key levers, and means operative in the restoring movement of the key levers to return all actuated segments to normal positions relative to such key levers.

In testimony whereof I affix my signature.

MYLES H. ROYER.
